ELEVATOR

Filed Dec. 7, 1921

Inventor

Jacob D. Lewis

By his Attorney L. N. Campbell

UNITED STATES PATENT OFFICE.

JACOB D. LEWIS, OF YONKERS, NEW YORK, ASSIGNOR TO OTIS ELEVATOR COMPANY, OF JERSEY CITY, NEW JERSEY, A CORPORATION OF NEW JERSEY.

ELEVATOR.

Application filed December 7, 1921. Serial No. 520,475.

My invention relates to controlling apparatus for electric current motors, more particularly as described and shown as a controlling apparatus for alternating current motors for elevators.

It has been found impractical heretofore in alternating current elevator installations to exceed a car speed of 400 F. P. M., especially so when the motor is run on a 60 cycles current. This is primarily due to the fact that it is impractical to build the driving or hoisting motor with a greater speed reduction than 3 to 1. With this speed reduction an elevator car running at 600 F. P. M. as its high speed would be retarded to 200 F. P. M. car speed, at which point the mechanical brake would be applied to bring the car to rest. At this car speed of 200 F. P. M. the moving masses of the elevator would still have considerable kinetic energy with the result that the car would slide, making it difficult to secure "good landings" and would also result in rapid deterioration of the brake linings.

The purpose of the present invention is to overcome these and other objections in alternating current elevator installations by providing means whereby the car low speed is reduced to say one-ninth of the high speed, thereby actually reducing the kinetic energy of the moving parts to say one eighty-first (1/81) part of its energy at high speed, so that no difficulty is experienced in making good stops, and resulting in a long life of the brake linings.

Another object of the present invention I show with the use of an induction motor as an auxiliary apparatus, that a current of one-third (1/3) line frequency can be obtained from its phase wound rotor so that the low speed winding of the main or hoisting motor can be thrown on this supply and thereby reduce its speed to one-third (1/3).

For a further object of the invention I employ the auxiliary induction motor as an impedance in series with the main or hoisting motor for the purpose of limiting the current to the hoisting motor, both to its high and low speed windings. This eliminates the stator resistance, commonly used prior to my invention; the present means will decrease the power consumption to a very considerable extent when there is a large number of starts and stops per car mile.

Other objects of the invention will appear hereinafter.

The invention in general consists in employing the usual electric A. C. hoisting motor in an elevator, together with a conventional type of hoisting rigging and brake apparatus, a main voltage supply of a standard value at 60 a standard frequency for the motor, and a supplementary low voltage supply at a low frequency to drive the hoisting motor at a definite rate of speed, the supplementary or low voltage being supplied from a motor generator set.

The accompanying drawing, illustrates diagrammatically a typical car switch controlled elevator, arranged in accordance with my invention.

The elevator as shown in the drawing comprises a two-speed A. C. electric hoisting motor, M, of the squirrel cage type, with two stator windings; supply mains, a, b, c, from which an alternating current is supplied to the windings of the motor and the controlling mechanisms, reversing switches, U and D, controlling the phase relation of current supplied to the motor, electromagnetically operated switches C, E, F, H and I, electromagnetic brake, B, diagrammatically shown, comprising a plurality of magnet coils, a centrifugally operated speed governor, J, diagrammatically shown, comprising a plurality of switch contacts successively made as the speed of the motor increases and one contact opened after the others are closed as hereinafter described, the governor being driven by the motor M, through the intermediation of a gearing 1, the governor when operating causing the successive operation of several of the elements of the controlling mechanism, as more fully pointed out hereinafter.

The different landings or stopping points are designated L and L', and the car switch by the letter K, and the car leveling switch by the letter N.

Referring now particularly to the supplementary or auxiliary controlling apparatus, it comprises an induction motor, G, of the slip ring type, employed as a generator, being driven by another induction motor M', of the squirrel cage type. The auxiliary apparatus, in conjunction with the certain other elements heretofore referred to, is employed automatically to supply to the low speed winding of the hoisting motor M, in the stopping operation, low voltage at a low frequency, reducing the speed of the said winding to a considerable extent, at which reduced speed the brake

can cause a good stop to be made at a landing. The above described auxiliary apparatus is also employed in the starting operation of the hoisting motor, M, as an impedance in series 5 with the said motor, for the purpose of limiting the flow of current to the said motor, both to its high and low speed winding. This eliminates the stator resistance, as at present used and will decrease the power consumption 10 to a very considerable extent where there is a large number of starts and stops per car mile. All of which has been told heretofore.

There are two cams, 2 and 3, positioned in the elevator hatchway at each floor landing. 15 The cams, 2, form one series and the cams, 3, form another series arranged in vertical planes. The cams, 2, are adapted to operate contacts, 5, and cams, 3, contacts 4, of the car leveling switch, N these contacts controlling electrical connections to reversing switches U and D, respectively, to effect maintaining either reversing switch closed when the hoisting motor, M, is operating on the low voltage, to effect the automatic leveling operation of the car in a descending or ascending direction to stop at a landing, depending on the position of the car relatively to the cams, constituting the car leveling zone.

Operation of the elevator as a whole and 30 through a complete cycle of operation of starting and stopping will now be given.

With the parts as illustrated in the drawing, the car is at rest, level with the second or top floor landing. Let it be assumed that it 35 is desired to bring the car to the first landing, by operating the lever, 6, of the car switch K, being thrown to an extreme position, to the left, as that is what an operator or attendant would do in operating the elevator to 40 cause it to descend, obtaining a full operating condition of the apparatus as a result as will be seen hereinafter. The operation of the car switch closes first a circuit for the winding, 7, of the electro-magnetically operated low-speed switch, E, as follows: from 45 supply main a, junction point 8, by wire 9, contact 10, of the up-reversing switch, U, by wire 11, junction point 12, by wire 13, junction point 14, by wire 15, contact 16, of the 50 car switch K, segment 17 on the car switch lever 6, and contact 18 of car switch, as the contacts 16 and 18 were bridged by the operation of the car switch lever 6, by wire 19, junction point 20, by wire 21, junction point 22, by wire 23, winding 7 of electromagnet switch E, by wire 24, junction point 25, by 55 wire 26, junction point 27, by wire 28, junction point 29, by wire 30, junction point 31, by wire 32, junction point 33, to supply main b. The winding 7 of the electromagnet switch E is therefore energized and the switch E closed. The closing of the switch completes 60 by its contacts, 34 and 35, a circuit for the down-reversing switch winding, 36, as follows: starting at this time at the contact 16

of the car switch, as up to this point the circuit remains unchanged, by segment 17 and contact 37 of the car switch, by wire 38, junction point 39, by wire 40, back contacts 41 of up-reversing switch U, by wire 42, junction 70 point 43, winding 36, of down-reversing switch D, junction point 44, by wire 45, contacts 34 and 35, of electromagnet switch E, by wire 46, junction point 25, to main b as before. The reversing switch D is therefore 75 closed, the contacts 47 and 48 engaging contacts 49 and 50, respectively, and contact 51 engaging contact 52, the back contacts 53 and 54 opening through the operation of the switch. The back contacts 53 are in circuit 80 with the winding of the up-reversing switch U, and when open prevent an operation of the up-reversing switch, likewise the contacts 41, spoken of hereinbefore, when open, prevent an operation of the down-reversing 85 switch D. The closing of contacts 47, 48, 49 and 50 completes the circuit for the low speed windings of the hoisting motor M. The brake magnet B, at the same time, receives current through wires 56, 57 and 58, and operates to lift the brake.

A switch, 55, will be closed by hand through which a source of supply is obtained from the mains, a, b and c, for operating the motor M', of the generator set, which motor 90 M', in turn operates the generator G.

Upon the closing of the contacts 47, 48, 49 and 50, of the down-reversing switch, the stator windings of the generator G are excited as well as the low speed stator windings 100 of the hoisting motor M. Circuits through each are as follows: from main a, junction point 8, by wire 59, contacts 50 and 48, by wire 60, junction point 61, by wire 62, junction point 63, by wire 64, junction point 65, by wire 66, through one stator winding of the generator G, by wire 67, contact 68, of switch I, by wire 69, junction point 70, by wire 71, contacts 72 and 73 of low-speed switch E, as they are now closed, by wire 74, contact 75 of switch C, by wire 76, through one low-speed stator winding of hoisting motor M, by wire 77, junction point 78, by wire 79, through the back contacts 80, of switch C, by wire 81, junction point 82, by wire 83, junction point 84, by wire 85, through a second low-speed stator winding of hoisting motor M, by wire 86, contacts 87, of switch C, by wire 88, contacts 89 and 90 of switch E, as they are now closed as we said before, by wire 91, junction point 92, by wire 93, contact 94 of switch I, by wire 95, through a second stator winding of generator G, by wire 96, junction 97, by wire 98, junction point 29, by wire 30, junction point 31, by wire 32, junction point 33, to the main b. The circuit for the remaining stator windings of both generator G and hoisting motor M, is as follows: from main c, junction point 99, by wire 100, through contacts 49 and 47 130

of down-reversing switch, by wire 101, junction point 102, by wire 103, junction point 104, by wire 105, through a third stator winding of generator G, by wire 106, contact 107, of switch I, by wire 108, junction point 109, by wire 110, junction point 111, by wire 112, through contacts 113 and 114 of switch E, as they are closed at this time, by wire 115; contact 116 of switch C, by wire 117, through a third low-speed stator winding of hoisting motor M, by wire 118, contact 119 of switch C, by wire 120, through back contacts 121 of switch C, by wire 122, junction point 82, to the main b as before traced, 15 in the preceding case of the other stator winding of both generator G and hoisting motor M.

The above illustrates that the operation first of switch E, secondly, of either reversing switch, — the down-reversing switch D, in the present case of description of operation,—as the elevator is operating in a downward direction of car travel, results in the stator windings of generator G and the low-speed 20 stator windings of the hoisting motor M being energized, and the hoisting motor M being operated. The stator windings of the generator G, being in series with the stator windings of the hoisting motor M, act as an 25 impedance to the flow of the current to the stator windings of the hoisting motor M, as well known to those versed in the motor art, the impedance being of a predetermined value, the torque of the hoisting motor being 30 low at this time results in a slow operation of the hoisting motor at this time. The rotor winding of the generator is open at this time and when closed by means of an electromagnetically operated low-speed accelerating switch, F, the operation of which will result 35 in a change of the impedance in both the stator and rotor windings of the generator G which reduces the total impedance to a smaller value, as is well known; also to a predetermined value. The torque of the hoisting motor now being greater than it was, the motor increases its speed, and consequently the speed of the elevator car.

I have illustrated only one step of acceleration of the hoisting motor M, in my invention, 40 that in which the operation of the low speed accelerating switch, F, closes and consequently short circuits the rotor winding of the generator, G; but it is obvious that more steps could be used with my system of control by the use of more electromagnetically operated switches or other devices, each to 45 cut out a resistance in series with the rotor winding of generator G, after which lastly the rotor winding would be short circuited as in the present case. The circuit for the winding of the electromagnetically operated switch, F, is as follows: from junction point 109, by wire 123, through the closed back contacts 124 of electromagnet switch H, by wire 50 125, through the winding 126 of electromagnet switch F, by wire 127, through the closed governor J, contacts 128, by wire 129, contact 94 of electromagnet switch I, to the main b, by way of wire 95, stator winding of generator G, by wire 96, junction point 97, by wire 98, junction point 29, by wire 30, junction point 31, by wire 32, and junction point 33. Thus the winding of switch F is subject to the counter E. M. F. of the hoisting motor. The 55 operation of electromagnet switch F, the contacts of which short circuit the rotor winding of generator G, results in an increase of speed of the hoisting motor M, as told hereinbefore. The circuit is from the slip ring 130, so by wire 131, contact 132 of electromagnet switch H, by wire 133, contacts 134 and 135 of electromagnet switch F, which are closed at this time, by wire 136, contact 137 of electromagnet switch H, by wire 138, slip ring 139; also slip ring 140, by wire 141, contact 142, of electromagnet switch H, by wire 143, contacts 144 and 145, they being closed at this time, by wire 146, contact 135 back to the rotor as before. The 60 closing of electromagnet switch F makes a circuit by means of its contacts 147 and 148, for the operation of the electromagnetically operated low and high speed accelerating switch I. The circuit for the winding of electromagnet switch I is as follows: from junction point 104, by wire 149, junction point 150, by wire 151, through the winding 152 of electromagnet switch I, by wire 153, junction point 154, by wire 155, through closed back 65 contact 156, of electromagnet switch C, by wire 157, junction point 158, by wire 159, through contacts 148 and 147 of electromagnet switch F, they being closed at this time, by wire 160, junction point 27, to main b, by wire 161, junction point 29, by wire 30, junction point 31, by wire 32, and junction point 33. The operation of electromagnet switch I in my controlling system, closing its three pairs 70 of contacts as a result short circuits the stator winding of generator G, the remaining impedance in series with the low speed stator windings of hoisting motor M has therefore been cut out, the torque of the hoisting motor 75 has become still greater and the result is a further increase of speed of the hoisting motor, which is now operating on its low speed windings alone. The contacts 161 and 162 of the governor switch J were originally open, but have closed during the operation of the hoisting motor M up to the present stage, but to which no especial significance is attached at this time other than that they have closed.

As a further operation in my system of control, there is the operation of the electromagnetically operated high and low speed switch C, the circuit for its winding 167, is as follows: from contact 16 of car switch K, the circuit up to this point from main a, being as 80 before traced, segment 17 on the car switch 120 85

lever 6, and contact 207 of the car switch, by wire 208, through closed back contacts 163 of the up-reversing switch U, by wire 164, junction point 165, by wire 166, through the 5 winding 167 of electromagnet C, by wire 168, junction point 158, to main b, by wire 159, contacts 148 and 147 of switch F, by wire 160, junction point 27, by wire 28, junction point 29, by wire 30, junction point 31, by wire 32, 10 and junction point 33. The electromagnet switch C therefore closes as a result of the last traced circuit closing through the winding 167. The electromagnet switch C in operating first opens its normally closed or back 15 contacts, after which for an instant both the low and high speed stator windings of the hoisting motor are in series with each other, together with the stator windings of the generator G, as the contacts of electromagnet 20 switch I, which in a previous operation short-circuited the said windings of the generator, are again open as the opening of one of the back contacts of electromagnet switch C has deenergized the electromagnet switch I. The 25 top or normally open contacts of electromagnet switch C in closing short circuits the low speed stator windings of the hoisting motor M. It thus follows that the high speed stator windings of the hoisting motor M, have been 30 energized, and that the stator windings of the generator G have been put in circuit with the high speed stator windings of the hoisting motor M, and act as an impedance to these windings, as the stator windings of the 35 generator did with the low speed stator windings of the hoisting motor M. As a consequence, the speed of the hoisting motor M is further increased as a result of the energizing of the high speed windings of the said 40 motor; the circuit for the current to the high speed stator windings of the hoisting motor at this time is from original supply main c, to junction point 104, and thence by wire 105, through a stator winding of generator G, by 45 wire 106, contact 107 of electromagnet switch I, by wire 108, junction point 109, by wire 110, junction point 111, by wire 112, contacts 113 and 114 of electromagnet switch E, by wire 115, contacts 116 and 119 of electromagnet 50 switch C, as they are now closed, by wire 118, through a high speed stator winding of the hoisting motor M, the windings being connected together at one of their ends which I have shown, we go through another high 55 speed stator winding, by wire 85, junction point 84, by wire 169, contacts 170 and 87 of electromagnet switch C, by wire 88, contacts 89 and 90, of electromagnet switch E, by wire 91, junction point 92, by wire 93, contact 94 of 60 electromagnet switch I, by wire 95, through a stator winding of generator G, by wire 96, junction point 96, by wire 98, junction point 29, by wire 30, junction point 31, by wire 32, and junction point 33, to main b. The circuit for the remaining high speed stator 65 windings of the hoisting motor is originally from supply main a, to junction point 65, and thence by wire 66, through a stator windings of generator G, by wire 67, contact 68, of electromagnet switch I, by wire 69, junction point 70 70, by wire 71, contacts 72 and 73, of electromagnet switch E, by wire 74, contacts 75 and 171 of electromagnet switch C, by wire 172, junction point 78, by wire 77, through a high speed stator winding of hoisting motor M, 75 and since all the high speed windings are joined together at one of their ends, the circuit passes through the wire 85, to the main b as previously traced.

The contacts 173 and 174 of the governor 80 switch J, have closed, due to the increase of speed of the hoisting motor M, after its high speed stator windings were energized, the closing of the said contacts serving further to increase the speed of the hoisting motor 85 M, by making a circuit for operating again the electromagnet switch I, which as shown before when the contact of the said switch are closed short circuit the stator windings of generator G, which acted as an impedance 90 to the current to the low speed stator windings of hoisting motor firstly, and to the current to the high speed stator windings of the said motor secondly. The circuit through the electromagnet switch I at this time is, from junction point 150, the feed coming from main 95 c, to this point, by wire 151, through the winding 152, of the switch, by wire 153, junction point 154, by wire 175, contacts 176 and 177, of electromagnet switch C, as they are 100 closed at this time, by wire 178, contacts 173 and 174 of governor switch J, by wire 179, contact 147, of electromagnet switch F, by wire 160, junction point 27, by wire 28, junction 105 point 29, to main b. The speed of the 110 hoisting motor M, increasing after the contacts 173 and 174 of governor switch J have closed, the hoisting motor M is now operating on full torque and consequently at its high speed to bring the elevator car to the first 115 landing L'. The contacts 128 of governor switch J open as a result, deenergizing electromagnet F, the rotor windings of generator G, being opened as a result.

In stopping, the car switch lever 6, is 115 brought to center and when normally done so the operation is as follows: first the electromagnet high and low speed switch C will be deenergized, opening the circuit to the high speed stator windings and closing the circuit 120 to the low speed stator windings of hoisting motor M. The electromagnet low and high speed accelerating switch I will open as a result of the opening of electromagnet switch C, inserting the generator G stator windings 125 in series with the low speed stator windings of hoisting motor M, the generator G stator windings again acting as an impedance to the current in the low speed stator windings of hoisting motor M, and, should the speed not 130

have decreased to a predetermined value, resulting in closing the contacts 128 of the governor switch J, the rotor windings of generator G will remain open, there will be 5 then the maximum impedance in windings of the generator G, in circuit with the low speed stator windings of the hoisting motor M, which causes the motor to slow down quickly.

It will be observed that the generator G 10 stator windings are inserted during the slow-down period, because at that time, the torque of the low speed stator windings of the hoisting motor M will be excessive, and therefore an efficient method of reducing the voltage 15 in the hoisting motor M is necessary. The contacts 128 of the governor switch J will have closed by this time, after which only the stator windings of the generator G are in circuit with the low speed windings of the 20 hoisting motor M. The car switch K may have been centered by this time, but it will be assumed that the speed of the hoisting motor M, is still great enough to hold closed the contacts 162 of the governor switch J, 25 through which a holding circuit is established to hold closed the electromagnet low speed switch E, the circuit being had from junction point 12, by wire 180, through contacts 162, by wire 181, junction point 22, to and 30 through the winding 7 of electromagnet switch E, to main b as before. The contacts 161, of governor switch J, likewise not having opened as yet provide a holding circuit for the down-reversing switch D, circuit is 35 as follows: from junction point 12, by wire 180, left hand contact 162, by wire 182, contacts 161, of governor switch J, by wire 183, junction point 184, by wire 185, contacts 52 and 51 of down-reversing switch D, by wire 40 188, junction point 43, through the winding 36 of reversing switch to main b as before. Governor switch J, contacts 162, opening at this time, the electromagnet switch E, opening as a result, cuts out of the circuit of 45 the low speed stator windings of hoisting motor M, the stator windings of the generator in the circuit to the windings of the hoisting motor M. The circuit to the stator winding of the generator G is now through the closed 50 back contacts 209 and 210 of the electromagnet low speed switch E. Through the other closed back contacts 189, a circuit for the operation of the electromagnet decelerating and micro-switch H, the circuit of which is as 55 follows: from the junction point 63, by wire 190, through the winding 191 of electromagnet switch H, by wire 192, through closed back contacts 189, of electromagnet switch E, by wire 193, and junction point 102 to main c. The back contacts 124 of electromagnet switch H, in opening deenergize electromagnet low speed accelerating switch F, resulting in the rotor windings of generator G being again opened. The closing of contacts 194 and 195 of electromagnet switch H

closed one side of the circuit for the down-reversing switch D. The circuit for the reversing switch D now being from junction point 44, by wire 45, contact 34, of electromagnet switch E, by wire 196, through contacts 194 and 195 of electromagnet switch H, by wire 197, junction point 27, by wire 28, and junction point 29, to main b, as before. During the interval between the opening of electromagnet low speed switch E and the closing of electromagnet decelerating switch H, the circuit for the reversing switch D was through the resistance 198. The reversing switch thereby being kept closed during the change-over period. The closing of contacts 137 and 199, 142 and 200, 132 and 201 of electromagnet switch H, placed in circuit with the low speed stator windings of hoisting motor M, rotor windings of the generator G, which now delivers a current to the said 85 windings of the hoisting motor M, the circuits are as follows: from slip ring 130, by wire 131, contacts 132 and 201 of electromagnet switch H, by wire 202, contact 73, of electromagnet switch E, by wire 74, contact 75, of electromagnet switch C, by wire 76, through a low speed stator winding of hoisting motor M, by wire 77, junction point 78, by wire 79, back contacts 80, of electromagnet switch C, by wire 81, junction point 82, by wire 83, junction point 84, by wire 85, through a low speed stator winding of hoisting motor M, by wire 86, contact 87, of electromagnet switch C, by wire 88, contacts 89, of electromagnet switch E, by wire 203, through contacts 200 and 142, of electromagnet switch H, by wire 141, to slip ring 140. Also from slip ring 139, by wire 138, through contacts 137 and 199, of electromagnet switch H, by wire 204, contact 114 of electromagnet switch E, by wire 115, contact 116, of electromagnet switch C, by wire 117, through a low speed stator winding of hoisting motor M, by wire 118, contact 119 of electromagnet switch C, by wire 120, through back contacts 121 of electromagnet switch C, by wire 122, junction point 82, back to the rotor of generator G, as traced before.

The generator G is supplying to the low speed stator windings of hoisting motor M power at a very low frequency, which results in a very slow operation of the hoisting motor and elevator car. For example, it will be assumed that the main supply line is 60 cycles current, and auxiliary motor M', which is a low resistance squirrel cage motor, and generator G are wound for 6 and 4 poles, respectively. The synchronous speed of motor M' is 1200 revolutions per minute. Then the frequency of the rotor current of generator

$$G = \frac{6-4}{2} \times \frac{1200}{60} = 20 \text{ cycles.}$$

The result of the exchange of energy of the

motor M' and generator G , can be easily computed being the power delivered to the hoisting motor for operating. Knowing the duty or load of the elevator, speed, counterweight and other constants, the power delivered by the generator G to the low speed stator windings of hoisting motor M is easily obtained by those versed in the elevator art.

Assume that the governor switch J , contact 161, open upon the arrival of the elevator car in the leveling zone. A circuit to maintain the down-reversing switch closed at this time is from junction point 12, by wire 13, junction point 14, through contacts 5, of the leveling switch N , as they are now closed, the roller 205, of the switch N having engaged cam 2, closing the contacts 5 as a result, by wire 206, junction point 39, to and through the down-reversing switch D , winding 36, as before traced, the other side of the circuit from the reversing switch winding being traced through the contacts 194 and 195 of the electromagnet switch H , as they are still closed. The elevator car platform coming opposite to the landing L' , whereupon the roller 205 of the leveling switch N rides off of the cam 2, opening the switch contacts 5, and effects the opening of the down-reversing switch D , and the electromagnet decelerating switch H . In this manner all the electrical circuits to the hoisting motor M , generator G , brake winding, etc., are opened, and the brake shoe is applied to bring the elevator car to rest.

In the event of the car overrunning the landing, contacts 4 of switch N will be closed by the roller 205 engaging cam 3 whereby circuits similar to those described for the down low speed operation by generator G will be closed to return the car to the floor level.

I have described my invention in connection with the operation of the down-reversing switch D , but it will be understood that the operation is the same in principle when the "up" switch U is operated.

In order to simplify the illustration and description, I have omitted from the drawing the usual safety devices such as the limit switches at the upper ends of the hatchway, the emergency switch in the car, the door contacts, etc., as they are unnecessary to illustrate my invention.

It will be understood that my invention is adapted for use with other types of elevator control than the one herein shown as for example, but not to exclude others, a push button elevator. I desire not to be limited to any particular number of low speed accelerating switches F ; they may be as numerous as desired, the greater the number used the greater the refinement of operation will be. Furthermore, I have for the sake of illustration shown a three phase system of alternating current, but my invention is

not confined to any particular number of phases. Furthermore, I wish it to be understood that my invention is not limited to the details of construction or arrangement of parts herein disclosed, and that various modifications might be made within the spirit and scope of the invention. 70.

I claim:

1. In an elevator control system, the combination of an A. C. hoisting motor of the squirrel cage type, with stator windings, a source of power of a certain voltage and frequency, means adapted to connect said source to the stator windings of the hoisting motor, a motor-generator set adapted to supply the hoisting motor with power of a low voltage and low frequency as compared with the voltage and frequency of said source, and speed responsive means adapted to connect the generator of the motor-generator set to the hoisting motor at a definite speed of the hoisting motor. 75 80 85

2. In an elevator control system, the combination of a multispeed A. C. hoisting motor comprising low speed stator windings, an electro-mechanical brake therefor, a source of power of a certain voltage and frequency, a motor-generator set comprised of a squirrel cage motor and a slip ring motor, the squirrel cage motor being adapted to drive the slip ring motor causing it to produce a low voltage of low frequency as compared with the voltage and frequency of said source, and speed responsive means adapted to effect a connection between the motor-generator set and the low speed stator windings of the hoisting motor in the operation of stopping the elevator, whereby the speed of the hoisting motor is reduced, and at which reduced speed the electro-mechanical brake can be applied 90 95 100 105 to cause a good stop of the elevator car to be made at a desired floor landing.

3. In an elevator control system, the combination of a multi-speed A. C. hoisting motor having low speed stator windings, a source of power of a certain voltage and frequency, a motor-generator set adapted to produce a low voltage at a low frequency as compared with the voltage and frequency of said source, and means for connecting the generator windings 110 in series with the low speed stator windings of the hoisting motor as an impedance in the operation of starting and stopping the elevator, whereby the flow of current from said source to the hoisting motor is limited. 115 120

4. In an elevator control system, the combination of a multispeed A. C. hoisting motor having low and high speed stator windings, a source of power of a certain voltage and frequency, a motor-generator set adapted to produce a low voltage at a low frequency as compared with the voltage and frequency of said source, and means for connecting the generator windings in series with the low and high speed stator windings of the hoisting motor 125 130

- as an impedance in the operation of starting the elevator, whereby the flow of current from said source to the hoisting motor is limited and external resistances for the stator windings eliminated.
5. In an elevator control system, the combination of an A. C. hoisting motor having low and high speed stator windings, a main high voltage supply for the motor, an A. C. auxiliary generator of the slip ring type, an elevator low speed switch adapted to connect in series the stator windings of the auxiliary generator and the low speed stator windings of the hoisting motor, an elevator low speed accelerating switch adapted to short circuit the rotor windings of the auxiliary generator, an elevator low and high speed accelerating switch adapted to short circuit the stator windings of the auxiliary generator, and an elevator high and low speed switch adapted, when none of its contacts are closed, to place the high speed stator windings of the hoisting motor in series with its low speed stator windings and the stator windings of the auxiliary generator and, when certain of its contacts are closed, to short circuit the low speed stator windings of the hoisting motor.
6. In an elevator control system, the combination of an A. C. hoisting motor having low and high speed stator windings, a main voltage supply for the motor, an A. C. auxiliary generator of the slip ring type, an elevator low speed switch adapted to connect in series the stator windings of the auxiliary generator and the low speed stator windings of the hoisting motor, an elevator low speed accelerating switch adapted to short circuit the rotor windings of the auxiliary generator, an elevator low and high speed accelerating switch adapted to short circuit the stator windings of the auxiliary generator, an elevator high and low speed switch adapted, when none of its contacts are closed, to place the high speed stator windings of the hoisting motor in series with its low speed stator windings and the stator windings of the auxiliary generator and, when certain of its contacts are closed, to short circuit the low speed stator windings of the hoisting motor, and an elevator governor switch adapted, when closed, to effect the short circuiting of the stator windings of the auxiliary generator, and the other set adapted, when open, to effect the opening of the rotor windings of the auxiliary generator.
7. In an elevator control system, the combination of an A. C. hoisting motor having low and high speed stator windings, a main high voltage supply therefor of standard value and frequency, reversing switches for the elevator, an auxiliary generator, having stator and rotor windings, and adapted to generate a current of low voltage at low frequency as compared with that of the main voltage supply for the hoisting motor, a switch operable to open the circuit between the main voltage supply and the hoisting motor, a switch adapted to close to connect together the rotor windings of the auxiliary generator and the low speed stator windings of the hoisting motor, and means to maintain closed one reversing switch during the period between the opening of said first named switch and the closing of said last named switch.
8. In an elevator control system, the combination of an A. C. hoisting motor having low speed stator windings, a main high voltage supply therefor of standard voltage and
9. In an elevator control system, the combination of an A. C. hoisting motor having low speed stator windings, a main high voltage supply therefor of standard value and frequency, reversing switches for the elevator, an auxiliary generator, having stator and rotor windings, and adapted to generate a current of low voltage at low frequency as compared with that of the main voltage supply for the hoisting motor, a switch operable to open the circuit between the main voltage supply and the hoisting motor, a switch adapted to close to connect together the rotor windings of the auxiliary generator and the low speed stator windings of the hoisting motor, and means to maintain closed one reversing switch during the period between the opening of said first named switch and the closing of said last named switch.
10. In an elevator control system, the combination of an A. C. hoisting motor having low speed stator windings, a main high voltage supply therefor of standard voltage and

- frequency, elevator reversing switches, an auxiliary generator having stator windings and rotor windings adapted to produce a current of low voltage at low frequency as compared with the main voltage supply for the hoisting motor, an elevator low speed switch adapted, when opened, to open the circuit between the main voltage supply and the hoisting motor, an elevator governor switch adapted, when opened, to open the elevator low speed switch, an elevator decelerating and micro switch adapted to connect together the rotor windings of the auxiliary generator and the low speed stator windings of the hoisting motor, and means automatically operable to open the circuit to the hoisting motor.
11. In an elevator control system, the combination of an A. C. hoisting motor, comprising low speed stator windings, an electro-mechanical brake, a main high voltage supply of a standard value at a standard frequency, an A. C. motor generator set comprised of a squirrel cage and a slip ring motor, the squirrel cage motor adapted to drive the slip ring motor causing it to produce a low voltage of low frequency, an elevator low speed switch adapted to effect a connection between the induced windings of the slip ring motor and the low speed stator windings of the hoisting motor in the operation of stopping the elevator, whereby the speed of the hoisting motor is reduced, and at which reduced speed the electro-mechanical brake can be applied to cause a good stop of the elevator car to be made at a desired floor landing.
12. In an elevator control system, the combination of an A. C. hoisting motor, comprising low speed stator windings, an electro-mechanical brake, a main high voltage supply of a standard value at a standard frequency, an A. C. motor-generator set comprised of a squirrel cage and a slip ring motor, the squirrel cage motor adapted to drive the slip ring motor causing it to produce a low voltage of low frequency, means adapted to disconnect the hoisting motor from the high voltage supply, and means to connect the induced windings of the slip ring motor and the low speed stator windings of the hoisting motor in the operation of stopping the elevator, whereby the speed of the hoisting motor is reduced, and at which reduced speed the electro-mechanical brake can be applied to cause a good stop of the elevator car to be made at a desired floor landing.
13. In an elevator control system, the combination of an A. C. hoisting motor, comprising low speed stator windings, an electro-mechanical brake, a main high voltage supply of a standard value at a standard frequency, a motor-generator set comprised of a squirrel cage and a slip ring motor, the squirrel cage motor adapted to drive the slip ring motor causing it to produce a low voltage of low frequency, an elevator low speed switch adapted to effect a connection between the induced windings of the slip ring motor and the low speed stator windings of the hoisting motor in the operation of stopping the elevator, whereby the speed of the hoisting motor is reduced, and at which reduced speed the electro-mechanical brake can be applied to cause a good stop of the elevator car to be made at a desired floor landing.
14. In an elevator control system, the combination of an A. C. hoisting motor, a main voltage supply therefor of a standard value at a standard frequency, an A. C. auxiliary generator, means adapted to connect in series the stator windings of the hoisting motor and the auxiliary generator, the generator having open rotor windings, and means adapted to short circuit the stator windings and rotor windings of the auxiliary generator.
15. In an elevator control system, the combination of an A. C. hoisting motor, having low speed stator windings, a main voltage supply therefor of a standard value at a standard frequency, an A. C. auxiliary generator, means adapted to connect in series the low speed stator windings of the hoisting motor and the auxiliary generator, the generator having open rotor windings, and means adapted to short circuit the rotor windings of the auxiliary generator, in the operation of starting the elevator.
16. In an elevator control system, the combination of an A. C. hoisting motor having low speed stator windings, a main voltage supply therefor of a standard value at a standard frequency, and a system of control for the hoisting motor, comprising an A. C. auxiliary generator, an elevator low speed switch adapted to connect in series the stator windings of the auxiliary generator and the low speed stator windings of the hoisting motor, and an elevator low speed accelerating switch adapted to short circuit the rotor windings of the auxiliary generator, in the operation of starting the elevator.
17. In an elevator control system, the combination of an A. C. hoisting motor having low speed stator windings, a main voltage supply therefor of a standard value at a standard frequency, and a system of control for the hoisting motor, comprising an A. C. auxiliary generator, an elevator low speed switch adapted to connect in series the stator windings of the auxiliary generator and the low speed stator windings of the hoisting motor, an elevator low speed accelerating switch adapted to short circuit the rotor windings of the auxiliary generator, and means adapted to short circuit the stator windings of the auxiliary generator.
18. In an elevator control system, the com-

- bination of an A. C. hoisting motor having low speed stator windings, a main voltage supply therefor of a standard value at a standard frequency, and a system of control for the hoisting motor, comprising an A. C. auxiliary generator, an elevator low speed switch adapted to connect in series the stator windings of the auxiliary generator and the low speed stator windings of the hoisting motor, 10 an elevator low speed accelerating switch adapted to short circuit the rotor windings of the auxiliary generator, and an elevator low and high speed accelerating switch adapted to short circuit the stator windings of the auxiliary generator. 15
19. In an elevator control system, the combination of an A. C. hoisting motor, a main voltage supply therefor, and a system of control for the hoisting motor, comprising an A. C. auxiliary generator, means adapted to connect in series stator windings of the hoisting motor and auxiliary generator, the generator having open rotor windings, means adapted to short circuit the rotor windings 25 of the auxiliary generator, and means adapted to short circuit the stator windings of the auxiliary generator.
20. In an elevator control system, the com-
- bination of an A. C. hoisting motor having low and high speed stator windings, a main voltage supply for the hoisting motor, and a system of control for the hoisting motor, comprising an A. C. auxiliary generator, means adapted to connect in series the stator windings of the auxiliary generator and the low and high speed stator windings of the hoisting motor, the generator having open rotor windings, and means adapted to short circuit the rotor windings of the auxiliary generator. 30 35 40
21. In an electric elevator control system, the combination of a multi-speed motor for raising and lowering the elevator car, a main power supply of a given frequency for said motor, means for effecting the various speeds 45 of said motor by suitably connecting its windings to said main power supply, an auxiliary power supply of a different frequency for said motor, and means for leveling the car with a desired floor, said means comprising 50 automatic means for effecting still another speed of said motor by suitably connecting its windings to said auxiliary power supply.

In testimony whereof, I have signed my name to this specification.

JACOB D. LEWIS.
